ICE CREAM FREEZER

Richard H. Jordan, Springfield, Mass., assignor
to Westinghouse Electric & Manufacturing
Company, East Pittsburgh, Pa., a corporation
of Pennsylvania

Application April 12, 1934, Serial No. 720,221

4 Claims. (Cl. 259—110)

My invention relates to ice cream freezers, and it has particular relation to improvements in the construction of freezers adapted for use in electric household refrigerators.

One satisfactory form of cream-freezing device capable of deriving the necessary cooling from the evaporator or ice-making compartment of a domestic refrigerator comprises a cream container equipped with an agitator adapted to be driven by an electric motor which preferably is attached to the container assembly and arranged to derive energization from the refrigerator supply circuit. Within my knowledge, however, all such freezing devices which have been utilized in the past have been subject to a number of operating difficulties, and it is to the overcoming of these difficulties that the present invention is directed.

Generally stated, the object of my invention is to improve the construction of freezers of the type under consideration.

A more specific object of my invention is to facilitate the removal of the agitator from the body of the solidified cream upon the completion of the freezing operation.

Another object of my invention is to provide improved means for breaking loose the restraining bond of ice which, during the freezing operation, forms between the freezer structure and the surface of the evaporator or ice-making compartment upon which it rests.

My invention, itself, together with additional objects and advantages, will best be understood through the following description of specific embodiments thereof when taken in conjunction with the accompanying drawing in which:

Figure 1 is a side elevational view, partially in section, of an ice cream freezer incorporating the improvements of my invention.

Fig. 2 is a view in end elevation of the device of Fig. 1.

Fig. 3 is a view of the open end of the cream container of the device of Fig. 1 showing the improved agitator of my invention installed therein.

Fig. 4 is a view in side elevation showing the manner in which the two assemblies comprised by the agitating device represented in Figs. 1 and 3 may be separated from each other.

Fig. 5 is a perspective view of the loosening member of my invention when removed from the freezer structure, and

Fig. 6 is a diagrammatic view of a preferred form of control system for the driving motor which forms a part of the illustrated freezer.

Referring to the drawing, the freezer structure, there illustrated comprises a cylindrical container 10, adapted to receive the cream or other material to be frozen, the open end of which container may be closed by a detachable lid or cover 12. To this cover is removably secured a gear casing 14 carrying an electric motor 16 which drives, through suitable reduction gearing housed inside of the casing, an agitator or stirring-assembly 18 disposed inside of the container. 10 The entire freezer structure is designed for lengthwise insertion into the ice-making compartment of a domestic refrigerator (not shown), an energizing circuit for the motor being established through a flexible cord 22 terminating in 15 a plug connection 24 which may be inserted into an outlet receptacle conveniently located, as on an interior wall of the refrigerator.

The motor 16 drives, at a suitably reduced speed, a shaft 32 which is provided with an end 20 projecting tongue portion 33 which fits into a similarly shaped recess in the end 34 of the shaft which forms a part of the agitator 18. This agitator shaft is carried by suitable journals or bearings 36 and 38 formed respectively in the 25 closed end of the cream container 10 and in the container cover 12.

When disassembled, the illustrated freezer comprises four separate parts or assemblies; the mixture container 10, the agitator 18, the removable cover 12 and the gear casing and motor assembly 14—16. To hold the cover firmly in place against the container end and to enable its ready detachment, a plurality of spring clamping members 26 are utilized to hook over the 35 cover edge in the manner shown, the seal being made liquid tight through the use of a gasket 40 of rubber or other resilient material. Attachment of the motor and gear casing assembly 14—16 to the cover plate 12 is effected 40 by means of a circular recess in the plate side in which recess the end of the casing 14 is held at the bottom by means of a small plate member 45 and at the top by means of a vertically movable latch device 47 carried by the cover plate. 45

Upon the completion of the cream-freezing operation, it is desirable to remove the agitator structure to facilitate a proper packing of the frozen mixture and to enable the mixture to be readily dipped out for consumptive purposes. 50 In all previous designs of agitators with which I am familiar, such removal necessitates, particularly in the case of the relatively small capacity containers comprised by refrigerator-type devices, a removal of a substantial portion 55

of the frozen mixture, which removed portion must be replaced in the container and properly packed, an operation which is laborious and wasteful of time. To overcome this disadvantage, 5 I have designed an agitator which comprises two separable assemblages only one of which need be removed upon the completion of the freezing operation.

As illustrated in the drawing, the complete 10 structure comprises the central driving shaft 90 and one or more stirring members 92 which are held in contact with the wall of the container 10 by means of cross bar members 94 and 96. As hereinbefore explained, the motor 16 is coupled 15 with shaft 90 through the gear box 14 so that when operated it functions to rotate the agitator at a proper rate of speed.

One of the named assemblages comprises the cross-bar member 94 and the stirring blades 92 20 to the closed-container ends of which the cross bar is attached through any suitable means represented in the form of screws 97 which, in co-operation with spring members 98, serve to hold the blades in their proper relative positions. The 25 second of the named assemblages comprises the cross bar member 96 which is fixed to the drive shaft 90 near its open-container end. A driving connection between the ends of this cross bar and the stirring blades 92 is established by means 30 of screws 102, each of which is adapted to slide into a suitably shaped recess 104 in the end of one of the blades.

Likewise a driving connection between the shaft 90 and the cross-bar 94 of the first named 35 assemblage is effected by making the cooperating section of the shaft of hexagonal or other non-round contour and providing the cross bar with a similarly shaped opening 100 into which the shaft is adapted to fit. Both of these connections 40 permit the cooperating members to slide axially relative to each other so that the second named assemblage may readily be withdrawn from the first, as is shown in Fig. 4.

Upon the completion of the cream-freezing operation, only the outer cross bar 96 and the drive shaft 90 need be withdrawn from the container, the inner cross bar 94 and the attached paddle members 92 being allowed to remain embedded 50 in the solidified mixture. As a result, no difficulty whatever is experienced in packing the cream, since practically none of it need be removed. Furthermore, because of the fact that the blades 92 and the inner-cross bar 94 are adjacent the sides and bottom of the cream container, respectively, their presence in no way interferes with a subsequent removal of the ice cream. The described two-part construction for 55 an agitator is, therefore, one of considerable merit and utility.

It will be understood that my improved agitator is not restricted in its application to freezers of the small-capacity refrigerator type with 60 which it has been illustrated, since it is apparent that it may, with equal success, be applied to mixture-solidifying devices of practically all sizes and types.

During the freezing operation, it is found that there forms between the lower portion of the freezer structure and the supporting shelf member, represented at 76, upon which it rests, a film or thin layer of ice which frequently is difficult to break when it is desired to remove the structure from the refrigerator compartment. 70 To overcome this difficulty, I provide means for readily breaking this restraining bond of ice,

which means preferably comprises a cam member 80 carried by a shaft 82, the protruding end of which fits into a journaled hole 84 at one side of the cover-accommodating face of the cream-container base structure. The other end of this 5 shaft carries a handle 86 which extends upwardly along one side of the motor 16 or which occupies some other position of ready accessibility.

When the illustrated handle 86 is moved toward the motor 16, the cam 80 is rotated and 10 forced downwardly into contact with the freezer-supporting shelf member 76, an action which loosens the freezer structure from the restraining ice bond. The bond having been broken, removal of the freezer is readily effected. 15

The illustrated loosening device possesses the advantage of being readily removable from the freezer structure with which it is used. When installed, as shown in Figs. 1 and 2, it is held in position by means of a suitable edge extension 88 20 (see Fig. 2) of the cover 12 adapted to overlap the loosener cam. Removal of the cover from the container thus allows the shaft 82 to be withdrawn from the journaled hole 84 so that the complete loosener assemblage, shown in Fig. 5, 25 may be separated from the related freezer mechanism. This feature is of distinct advantage in facilitating the washing of the cream container and cover assemblages. The design illustrated is further unique in that it permits the user to grasp 30 the handle 86 and the motor 16 and by forcing them toward each other readily produce the necessary force for breaking the ice bond.

The freezer structure thus far described is, exclusive of the improved agitator and loosener, 35 similar to that disclosed and claimed in my co-pending application, Serial No. 686,762, filed August 25, 1933, and assigned to the same assignee as is this invention. That application further explains and claims the use of an intermittent-energization control system for the agitator driving motor, which system functions to reduce the effective heat losses dissipated during operation and thereby allows, without appreciably burdening the cooling capacity of the refrigerator 45 in which the freezer is used, the use of a motor sufficiently strong to continue an intermittent agitation of the mixture until it has been almost completely solidified.

In the effecting of such intermittent control, 50 the use of a timing device in the form of a thermostat equipped with a heater has been found especially satisfactory since such a combination may be made completely automatic in its operation and further is susceptible of time-on to time-off adjustment through a relatively wide range. Thus one preferred form of such control equipment comprises a thermostat, diagrammatically represented at 60 in Fig. 6, which is surrounded 55 by a suitable casing, represented at 61 in Figs. 1 and 2, which casing is shown as being suspended 60 from the lower side of the gear box 14.

The represented thermostat comprises a bimetallic disc 62 which, in the downwardly curved 65 position illustrated, biases movable contact members 64 into engagement with stationary contact members 66 to thereby complete an energizing circuit for the motor 16. Such circuit completion also energizes a resistor 68 which heats the disc 70 and causes it to reverse its curvature with a snap action. The resulting disengagement of the thermostat contacts discontinues energization of the motor and heater. When the disc temperature again drops to a given low value, the disc 75

snaps back to the illustrated position and thus causes the described cycle to be repeated.

Preferably each period of motor energization is of the order of three or four seconds while each period of deenergization is of the order of three or four minutes. For thermostats of commercially available design, I have found that when the illustrated mounting below the gear box structure is utilized, which location is desirable since it provides a unitary construction for the motor and its control means, the cooling of the thermostat disc does not proceed as rapidly as is necessary to effect the above specified cycle.

To overcome this difficulty, I increase the rate of disc cooling by attaching to the lower surface of the thermostat casing 61, which casing is preferably of molded insulating material, a plurality of metallic button members 70 and support this casing from the gear box structure by means of screws 72 adapted to permit of a sliding movement along their length. Compression springs 74 then bias the casing downwardly and thereby maintain the button members 70 in contact with the supporting shelf member 76 of the evaporator or ice-making compartment upon which the freezer rests, as shown in Fig. 2. Upon endwise insertion into the compartment, a beveled portion 78 assures that the casing will be forced upwardly to the shelf-contacting position illustrated.

By virtue of this contact the heat stored in the thermostat disc 62 is effectively dissipated to the relatively cold shelf 76 and the desired cycle of intermittent motor control is thereby effected with thermostatic devices of commercial design. It will be understood that this expedient is the equivalent of mounting the thermostat 60 in direct contact with the cream container 10 for example. It possesses, however, the before-named advantage of providing a unitary construction for the motor and its control means and hence, in practice, is of utility.

Although I have shown and described certain specific embodiments of my invention, I am fully aware that many modifications thereof are possible. My invention, therefore, is not to be restricted except insofar as is necessitated by the prior art and by the scope of the appended claims.

50 I claim as my invention:

1. In combination with an ice-cream freezer adapted to be supported by the cooling unit of a refrigerator, said freezer comprising a container structure and a removable cover member therefor, means for breaking ice which may form between the freezer and the cooling unit surface

upon which it rests, said means comprising a shaft, a journalled opening near the bottom of said container structure for receiving one end of said shaft, a cam carried by the protruding portion of said shaft, and a handle for rotating the shaft to cause said cam to bear against the said cooling unit surface, the positioning of said journalled opening being such that an edge of said cover member when installed, overlaps said cam to prevent said shaft from being withdrawn from the opening.

2. In combination with an ice-cream freezer adapted to be supported by the cooling unit of a refrigerator, said freezer comprising a container structure and a removable cover member therefor, means for breaking ice which may form between the freezer and the cooling unit surface upon which it rests, said means comprising a shaft, a journalled opening near the bottom of said container structure for receiving one end of said shaft, a cam carried by the protruding portion of said shaft, and a handle for rotating the shaft to cause said cam to bear against the said cooling unit surface, the positioning of said journalled opening being such that a removal of said cover member, one edge of which overlaps said cam, allows said shaft to be withdrawn from the opening.

3. In combination with an ice-cream freezer adapted to be supported by the cooling unit of a refrigerator, said freezer comprising a container, an agitator therein, a detachable cover therefor, an electric motor carried by said cover, and structure for operatively connecting the motor with the agitator, the combination of a motor-control thermostat supported from the lower portion of said structure, a casing for said thermostat, and means for biasing said casing into contact with the cooling unit surface upon which the freezer rests.

4. In combination with an ice-cream freezer adapted to be supported by the cooling unit of a refrigerator, said freezer comprising a container, an agitator therein, a detachable cover therefor, an electric motor carried by said cover, and structure for operatively connecting the motor with the agitator, the combination of a motor-control thermostat provided with a heater, a casing surrounding said thermostat and heater means for supporting said casing from the lower portion of said structure, and means for biasing said casing into contact with the cooling unit surface upon which the freezer rests to enhance the transfer of heat thereto.
